UNITED STATES PATENT OFFICE.

CHARLES R. GREY, OF BILLINGS, MONTANA.

TRASH-SEPARATOR FOR BEETS AND BEET-TAILINGS.

1,296,383.

Specification of Letters Patent. Patented Mar. 4, 1919.

Application filed March 13, 1916. Serial No. 83,925.

To all whom it may concern:

Be it known that I, CHARLES R. GREY, a citizen of the United States, residing at Billings, in the county of Yellowstone and State of Montana, have invented or discovered 5 certain new and useful Improvements in Trash-Separators for Beets and Beet-Tailings, of which the following is a specification, reference being had therein to the accompanying drawings.

This invention relates to machines for picking over vegetables, more particularly beets from which sugar is to be extracted, for the purpose of removing twigs, leaves, 15 and other trash as well as to separate out the "tailings" or broken roots too small to be of any value in the subsequent operations.

One object of the invention is to provide a machine of the character referred to adapted 20 to carry on its operations in an automatic and continuous manner, without the assistance of any other operator than the one who feeds the machine.

Another object of the invention is to provide 25 a machine of the character described, which is self-cleaning, or in other words, which will not become clogged with broken twigs, leaves or other trash.

Another object is to provide means in such 30 a machine whereby the beets are momentarily retarded in their travels until they have been thoroughly freed from trash.

Another object of the invention is to provide 35 a machine for the purpose specified, which is simple in its construction, consistent with the functions to be performed, and whose parts may be readily replaced when worn.

The foregoing and other objects of the 40 invention, together with means whereby the same may be carried into effect, will best be understood from the following description of one form or embodiment thereof illustrated in the accompanying drawings. It 45 will be understood, however, that the particular construction described and shown has been chosen for illustration purposes merely, and that the invention, as defined by the claims hereunto appended, may be otherwise practised without departing from the spirit 50 and scope thereof.

In said drawings:

Figure 1 is a top plan of a beet washing

machine constructed in accordance with the invention;

Fig. 2 is a longitudinal section through the entire machine taken substantially on the line 2—2, Fig. 3;

Fig. 3 is a transverse section taken on the line 3—3 of Fig. 2; and

Fig. 4 is a detail section on the line 4—4, Fig. 2.

With reference to the drawings, the machine comprises side members 1, which are preferably inclined as shown in Fig. 2. 65 Journalized at the lower and upper ends of the side members are shafts 2 and 3, respectively. Extending transversely to the side members 1 are bars 10 which support V-shaped troughs 11, which receive the lugs 8 70 of the chains and sprocket wheels 4 and 5. These sprocket wheels or pulleys are formed with peripheral V-shaped grooves, and the pulleys or wheels 4, which, in each series, alternate with the wheels 5, are in addition 75 provided with radial flanges 6.

Connecting oppositely disposed pulleys on the shafts 2 and 3, respectively, are chains 7 composed of pivoted links. These links are provided at their inner sides with inwardly extending V-shaped lugs 8, which engage the peripheral grooves of the pulleys 4 and 5, and at their outer sides with outwardly-projecting, cornered lugs 9. Extending transversely and secured to the side 85 members 1 are bars 10 which support V-shaped troughs 11, which receive the lugs 8 of the chains and thereby support the upper stretches of the chains, so that the weight 90 of the beets on the top of the chains will not cause sagging thereof, and, to that end, a trough is provided for each chain.

Power from any suitable source is applied to the shaft 3, for the purpose of rotating the same, through suitable transmission connections, herein shown as a sprocket chain 12^a coöperating with a sprocket wheel 12 fast upon one end of said shaft. Fast upon the opposite end of the shaft 3 is a sprocket wheel 13 connected by a chain 15 with a 100 sprocket 14 fast upon the shaft 2. The sprockets 13 and 14 are of different diameters, so that the shafts 2 and 3 rotate at different speeds, preferably in the ratio of one to three. The pulleys 4 are fast upon 105 their respective shafts, while the pulleys 5

are loose thereon, and each pulley 4 of one series is arranged opposite a pulley 5 of the other series, so that each chain 7 passes about a pulley 4 of one series and a pulley 5 of the other series. It therefore follows that adjacent chains of the series are driven from the shafts 2 and 3, respectively, and therefore travel at different speeds, while alternate chains of the series are driven from 10 the same shaft 2 or 3, and therefore travel at equal speeds. The direction of drive is such that the upper stretches of the chains travel upwardly and the lower stretches downwardly, as indicated by the arrow on 15 Fig. 2.

Extending transversely across the machine, and mounted in bearings 16, are rods 17 supporting downwardly extending retarding fingers 18, which are formed of 20 plates secured at their upper ends between the ears of castings 19 mounted on the rods 17 and having upwardly extending arms 20. Stop rods 21 are located adjacent the rods 17 and are adapted to form abutments for 25 the fingers 18, which are held thereagainst by coiled springs 22, secured at their opposite ends, respectively, to the arms 20 and to transverse rods 22^a supported at their ends by the side members of the frame. At the 30 upper portion of the machine, and extending transversely thereof, is a rod 23 supporting a plurality of fingers 24 whose lower ends are arranged in proximity to the chains 7 adjacent their points of engagement with the pulleys of the upper series. At one side 35 of the machine is a water supply pipe 25 provided with branch pipes 26, which extend across the machine and behind the retarding fingers 18, and are provided with perforations on their under sides for the purpose 40 of spraying water upon the chains and the material carried thereby. Disposed between the stretches of the chains is a trough 27 for the purpose of conducting the water and 45 trash, which passes through the spaces between the chains, toward the lower end of the machine toward a waste pipe or the like, (not shown).

The operation of the machine is as follows:

The beets or other vegetables, with the accompanying trash, tailings, etc., are deposited, by any suitable means, upon the upper surfaces of the chains 7, adjacent the upper 55 end of the machine, and tend to gravitate downwardly toward the lower end thereof, such downward movement being retarded, to a greater or less extent, by the upward movement of the chains. During this downward movement the beets are subjected to jets of water from the pipes 26 which tend to impel the beets downwardly, this impulse being, in part, counteracted by the retarding fingers 18, said beets being finally discharged at the lower end of the machine. 60

The twigs, sticks, and other trash falling upon the chains become entangled with the lugs 9 and, as adjacent chains travel at different speeds, are broken up and pass, with the water from the pipes 26, between the 70 chains and into the trough 27. Any material which may be carried by the lugs 9 to the top of the machine will drop from the chains as they pass over the pulleys of the upper series. Should any beet, by reason of 75 the peculiar formation of its root, or otherwise, be carried by the lugs 9 to the top of the machine, it will be disengaged from the chains by the fingers 24 and again permitted to gravitate downwardly. Any root or other 80 object becoming wedged between adjacent chains will be dislodged by the flanges 6 of the pulleys 4.

Having thus described my invention, what I claim as new and desire to secure by Letters Patent is:

1. A machine of the character described comprising a series of endless carriers arranged at an inclination to a horizontal plane and positively driven means for said carriers to cause adjacent carriers to move at different speeds while alternate carriers move at the same speed. 90

2. A machine of the character described comprising a series of inclined carriers provided with outwardly projecting cornered lugs, and means for actuating said carriers to cause adjacent carriers to move at different speeds while alternate carriers move at the same speed. 95

3. A machine of the character described comprising a series of carriers arranged at an inclination to the horizontal and spaced from one another, and positively driven means for actuating said carriers to cause adjacent carriers to move at different speeds while alternate carriers move at the same speed. 100

4. A machine of the character described comprising a series of spaced carriers arranged at an inclination to the horizontal and provided with outwardly projecting cornered lugs, and positive means for actuating said carriers to cause each of said carriers to move at a continuously greater or less speed than that of adjacent carriers. 110

5. A machine of the character described comprising an inclined frame, endless chains arranged to travel longitudinally of the frame, cornered lugs on the outer sides of the chains, and positive means for actuating the chains to cause their upper stretches to move upwardly and for causing each of said chains to move at a continuously greater or less speed than that of adjacent chains. 120

6. In a machine of the character described, the combination with an inclined frame, of shafts near the opposite ends of said frame, each shaft being provided with a series of pulleys of different sizes alternating with 125

each other, and alternate pulleys being fast on said shafts while the other alternate pulleys, between said first-named pulleys, are loose on said shafts, a series of endless carriers moving upwardly at their upper stretches and each of which runs from a fast pulley on one shaft to a loose pulley on the other shaft, and means for driving said shafts at different speeds; whereby alternate carriers will be caused to travel at different speeds while the intervening alternate carriers travel at the same speed.

7. In a machine of the character described, the combination with an inclined frame, of shafts near the opposite ends of said frame, each shaft being provided with a series of pulleys of different sizes alternating with each other, and alternate pulleys being fast on said shafts while the other alternate pulleys, between said first-named pulleys, are loose on said shafts, a series of endless carriers moving upwardly at their upper stretches and each of which runs from a fast pulley on one shaft to a loose pulley on the other shaft, said carriers having cornered lugs projecting upwardly at their upper stretches, and means for driving said shafts at different speeds; whereby alternate carriers will be caused to travel at different speeds while the intervening alternate carriers travel at the same speed.

8. In a machine of the character described, the combination with an inclined frame, of shafts near the opposite ends of said frame, each shaft being provided with a series of pulleys of different sizes alternating with each other, and alternate pulleys being fast on said shafts while the other alternate pulleys, between said first named pulleys, are loose on said shafts, a series of endless carriers moving upwardly at their upper stretches and each of which runs from a fast pulley on one shaft to a loose pulley on the other shaft, and means for driving said shafts at different speeds; whereby alternate carriers will be caused to travel at different speeds while the intervening alternate carriers travel at the same speed, and spring-pressed fingers above and coöperating with said carriers to retard the downward movement, by gravity, of the objects being operated upon.

9. In a machine of the character described, the combination with an inclined frame, of shafts near the opposite ends of said frame, each shaft being provided with a series of pulleys of different sizes alternating with each other, and alternate pulleys being fast on said shafts while the other alternate pulleys, between said first-named pulleys, are loose on said shafts, a series of endless carriers moving upwardly at their upper stretches and each of which runs from a fast pulley on one shaft to a loose pulley on the other shaft, and means for driving said shafts at differ-

ent speeds; whereby alternate carriers will be caused to travel at different speeds while the intervening alternate carriers travel at the same speed, and a series of fingers near the upper ends of said carriers to prevent the material from being carried over said upper ends.

10. In a machine of the character described, the combination with an inclined frame, of shafts near the opposite ends of said frame, each shaft being provided with a series of pulleys of different sizes alternating with each other, and alternate pulleys being fast on said shafts while the other alternate pulleys, between said first-named pulleys, are loose on said shafts, a series of endless carriers moving upwardly at their upper stretches and each of which runs from a fast pulley on one shaft to a loose pulley on the other shaft, and means for driving said shafts at different speeds; whereby alternate carriers will be caused to travel at different speeds while the intervening alternate carriers travel at the same speed, and means for spraying with water the objects being cleaned.

11. A machine of the character described comprising an inclined frame, transverse shafts near each end thereof, pulleys on the shafts, alternate pulleys on each shaft being of different sizes and alternate pulleys being fast thereon, endless chain carriers extending longitudinally of the frame and passing around the pulleys, cornered lugs on the outsides of the chains, a fixed sprocket on each shaft, one of said sprockets having a different diameter from the other, a chain connecting said sprockets, and means for driving one of said shafts to cause the upper stretches of said carrier to move upwardly, and whereby adjacent carriers are given different speeds.

12. A machine of the character described comprising an inclined frame, transverse shafts at each end thereof, pulleys fixed to said shafts and having annular peripheral V-shaped grooves, loose pulleys on said shafts alternating with said fixed pulleys, endless chain carriers which travel longitudinally of the frame and pass around said pulleys, V-shaped lugs on the inner sides of said chain carriers and which lugs engage the grooves of the pulleys, a V-shaped trough under the upper stretch of each chain for receiving the said V-shaped lugs to support said chain carriers, and means for actuating said carriers to cause the upper stretches thereof to move upwardly.

13. A machine of the character described comprising an inclined frame, a series of spaced endless chain carriers arranged to travel longitudinally of the frame, lugs on the outer sides of the chains, retarding fingers arranged transversely of the frame and adjacent the chains, a water supply pipe con-

tiguous to the frame and having perforated branch pipes arranged adjacent said retarding fingers, and means for actuating the said carriers to cause the upper stretches thereof to move upwardly.

14. A machine of the character described comprising a series of carriers arranged at an inclination to the horizontal and spaced from one another, means for actuating said carriers to cause the same to move upwardly,

Copies of this patent may be obtained for five cents each, by addressing the "Commissioner of Patents, Washington, D. C."

means for discharging jets of water upon vegetables on said carriers to impel the same downwardly, to wash said vegetables, and to force material separated therefrom between said carriers, and means for momentarily retarding said vegetables for the action of said jets.

In testimony whereof I affix my signature,

CHARLES R. GREY.
